COMBINATION PACKAGE AND DISPENSER

Ben Nash, Short Hills, N. J., assignor to Rogers Imports Inc., New York, N. Y., a corporation of New York

Application July 11, 1942, Serial No. 450,597

6 Claims. (Cl. 206—42)

This invention relates to the packaging and dispensing of very small articles and more particularly to the efficient packaging and convenient dispensing of small cigarette lighter flints.

Prior to the instant invention small articles such as lighter flints have been packaged in conventional containers and the handling of the small articles has been difficult. Lighter flints are so small that one must be very careful indeed to pick up a flint from a mass of flints with the fingers and without the use of an instrument. In an endeavor to pick up one flint several flints may be picked up and some of them dropped and consequently lost. Some prior attempts have been made to package flints in individual compartments in a multiple flint container. Such previous packages have been awkward to handle and expensive to manufacture. Further, the dispensing of flints from prior packages one at a time has not been as convenient as is desired by the user.

It is an object of the instant invention to teach a novel combination package and dispenser for small articles such as lighter flints.

It is a further object of the invention to teach the construction of the combination package and dispenser for small articles which will be convenient to hold in the hand of the user to operate so as to dispense one small article at a time without spilling the single article to be dispensed or other articles contained in the package.

Still another object of the instant invention is to teach the construction of a novel slidable combination package and dispenser for small articles which are to be conveniently dispensed one at a time which package will prevent the premature dispensing of the article to be dispensed and which is adapted to be accurately and conveniently controlled by the user.

Other objects and the nature and advantages of the invention will be apparent from the following description taken in conjunction with the accompanying drawing, wherein:

Figure 1 is a plan view of a combination package and dispenser in accordance with the invention with the slidable member in neutral position and all the articles within the package securely housed;

Figure 2 is a plan view of the package dispenser shown in Figure 1 with the slidable element pushed to the left prior to dispensing of the first article to be dispensed;

Figure 3 is a view similar to Figure 2 with the slidable element pulled an additional distance to

the left to place the first article to be dispensed in dispensing position.

Figure 4 is a transverse sectional view taken along line 4—4 of Figure 3 and looking in the direction of the arrows.

Referring to the drawing, the generally rectangular slidable element 10 of relatively thick section as shown in Fig. 4 is formed with rounded portions 11 at diagonally opposed corners of the element 10. These rounded corners 11 form convenient pushing portions adapted to be pushed by the thumb of the user. In Figure 2, for example, the slidable element 10 has been pushed to the left by the action of the thumb of the user on the rounded corner 11 at the right side of the element 10.

The slidable element 10 is provided with a plurality of rectangular pockets 12 with the major axis of the rectangular pockets disposed at an angle of less than 90° to the longitudinal axis of the slidable element 10. An angle of from approximately 45° to 51° is preferred. Each of the pockets 12 are adapted to house a small article such as a cigarette lighter flint 13. Each of the cigarette lighter flints is in the form of a small cylinder.

Coating with the slidable element 10 and forming a cover for each of the pockets 12 is the generally flat tubular body 14 within which the slidable element 10 is adapted to slide. The body 14 is preferably made of transparent material such as cellulose acetate or ethyl cellulose or other plastic or other suitable material such as glass or Celluloid, for example. It is contemplated that the body 14 may also be made of vinylite.

The slidable element 10 may be made of wood, cardboard, plastic or metal. The flints 13 or other similar small articles to be packaged and dispensed form no part of the instant invention and the nature of these articles is conventional.

While the body 14 has been disclosed in the drawing as a complete tube, it is contemplated that other sections differing from that shown in Figure 4 may be utilized with the provision, however, that the top side 15 of the body 14 covers the pockets 12 and with the further provision that a portion or portions of the body 14 cooperate with the element 10 so that the element 10 may slide with respect to the body 14 and be secured thereto in a manner not affecting the slidable relation described. For example, the bottom side 16 of the body 14 may be broken in order to conserve material or for other reasons.

The body portion 14 is provided with angled

ends 17 generally parallel to the axis of the pockets 12.

In assembling and loading the combination package and dispenser, the small articles to be housed and dispensed such as the flints 13 are placed within the pockets 12 of the slidable element 10 and then the element 10 is slid within the body 14 until it takes the neutral position shown in Figure 1. These loaded packages are convenient to stack and to hold individually in the user's hand.

The package, as shown in Figure 1, is fool-proof from the point of view that jarring of same will not cause premature dispensing of one of the small articles. Even if one of the rounded corners 11 is pushed to the position shown in Figure 2 no dispensing can take place. For dispensing to take place it is necessary to pull on one of the exposed ends of the slidable element 10 while holding the body 14 or moving the body 14 in the opposite direction.

When it is desired to dispense one of the small articles such as the flints 13, and the package is in the position shown in Figure 1, the user pushes one of the rounded corners 11 so that the combination package and dispenser is in the position shown in Fig. 2. Then the user may easily, accurately, conveniently and without awkwardness pull the extended end of the element 10 to the position shown in Figure 3 so that one of the articles to be dispensed is in dispensing position. Then the package is easily tilted so that the flint falls into the palm of the user's hand. The sloping ends 17 of the body 14 cooperate with the rounded exposed corners 11 of the element 10 to effect this positive and convenient action. The sloping arrangement of the pockets 12 make it necessary to move the slidable element 10 a relatively long distance in an axial direction in order to effect dispensing. This makes for ready control on the part of the user when effecting dispensing of the small articles such as the flints 13.

It will be obvious to those skilled in the art that various changes may be made without departing from the spirit of the invention and therefore the invention is not limited to what is shown in the drawing and described in the specification but only as indicated in the appended claims.

What is claimed is:

1. A relatively long, narrow, flat combination small article package and dispenser comprising a relatively long, narrow, pocketed planar

member having rounded portions at diagonally opposed corners, the pockets within the planar member being generally rectangular in shape and having a major axis disposed at an angle less

5 than 90° to the axis of said member, a relatively long narrow cover cooperating in slidable relation with respect to said member, the two remote ends of said cover being formed at an angle generally parallel to the axis of the pockets in 10 said member, said member being longer than said cover, the two rounded portions of said member protruding from said cover when said member is disposed centrally of said cover, the first of said pockets in said member being so located there- 15 within that when one of the rounded corners is pushed against one of said remote ends of said cover less than the major portion of said first pocket is exposed at the opposite end of said member.

20 2. The structure recited in claim 1, the major axis of said pockets being disposed at an angle of substantially 45° to the axis of said member.

3. The structure recited in claim 1, said cover being substantially tubular in section and transparent.

25 4. The structure recited in claim 1, said element being fabricated of cardboard.

5. A combination package and dispenser for cigarette lighter flints comprising a cover and a 30 slidable pocketed element adapted to cooperate with said cover, the pockets in said slidable element being long and narrow and arranged obliquely with respect to the major axis of said 35 slidable element, said slidable element being longer than said cover, the slidable element being provided with rounded portions at diagonally opposed corners, the ends of said cover which are most remote from each other being formed at an 40 angle generally corresponding to the angle of the axis of each of the pockets within said slidable member.

6. A flint combination package and dispenser comprising a transparent cover and a pocketed 45 slidable member, the first of said pockets in said member being so disposed in said member as to partially expose said first pocket but prevent premature dispensing therefrom when said member is pushed in at one end thereof up to the 50 corresponding end of said cover so as to require a pull on the opposite exposed portion of said member to effect dispensing of the first article from the first pocket in said member.

BEN NASH.
